E. J. REICH

TERMINAL CONNECTION FOR ELECTRODES

Filed July 30, 1923

INVENTOR
Edwin J. Reich
BY
Panekovich
his ATTORNEY

UNITED STATES PATENT OFFICE.

EDWIN J. REICH, OF BROOKLYN, NEW YORK, ASSIGNOR TO THE MANHATTAN ELECTRICAL SUPPLY COMPANY, OF NEW YORK, N. Y., A CORPORATION OF MASSACHUSETTS.

TERMINAL CONNECTION FOR ELECTRODES.

Application filed July 30, 1923. Serial No. 654,624.

To all whom it may concern:

Be it known that I, EDWIN J. REICH, a citizen of the United States, residing at Brooklyn, New York, in the county of Kings and State of New York, United States of America, having invented certain new and useful Improvements in Terminal Connections for Electrodes, do hereby declare that the following is a full, clear, and exact description of the same.

This invention relates to new and useful improvements in terminal connections for electrodes.

The object of the present invention is to provide a terminal connection which is adapted to make good contact with the carbon or other electrode, which may be readily applied preferably by means of automatic machinery, and which will be firmly held in place while the battery is in use.

With these objects in view I provide a structure to be hereinafter disclosed more in detail and various inventive features of which are defined in the appended claims.

The invention is illustrated in the drawing, showing a dry cell carbon electrode or pencil partly in section to display the construction of the preferred embodiment of the present invention.

The upper end of a carbon electrode 1 terminates in a tapering bead 2 and is longitudinally perforated at 3 to a slight depth. A dowel 4 is forced with its longitudinally corrugated shank within the hole 3 and into firm contact with the carbon. The downward movement of the dowel 4 is limited by an annular projection 5 provided thereon or fastened thereto by any suitable means. The dowel may be forced into the carbon until the shoulder 5 engages the top of the carbon pencil 1.

The upper part of the dowel is screw-threaded at 6 to receive the nut by means of which the wires are usually attached to the connector. A crown cap 7 having the usual fluted or corrugated petticoat 8 is provided with a square hole in its center which fits over a squared enlargement 9 on the dowel provided between the screw-threaded portion 6 and the shoulder 5. The cap 7 will rest on top of the shoulder 5. The height of this squared portion 9 is about

twice that of the thickness of cap 7, and after the cap is put in place with the square hole over 9, a blow is delivered on the shoulder formed by the squared portion 9 in the direction of the axis of the dowel for driving the dowel into the carbon pencil. Due to this blow, part of the metal in the enlargement 9 will be forced outward and will form a bead 10 by means of which the cap 7 will be firmly held in place.

The corrugated petticoat 8 of the cap is forced over the bead 2 on the upper end of the carbon pencil by any suitable means, such as is employed in bottle capping machinery.

The corrugated shank of the dowel 4 provides a fair contact with the carbon and is fairly effective in counteracting the loosening of the dowel when the binding screw is tightened over the screw threaded end 6. However, this in itself is insufficient to withstand long and hard usage. The cap 7 with its fluted petticoat provides a further means for making contact with the carbon. Due to the fact that these carbon pencils can practically not be made uniformly round, round caps do not make as good contact as corrugated caps which are forced firmly to grasp the carbon at the indentations. The cap 7 holds the dowel in place through the agency of the squared portion 9, and the enlargement between the bead 2 of the carbon pencil and the petticoat 8 of the cap will also aid in preventing the turning movement of the dowel. The dowel will resist longitudinal movement due to friction with the carbon pencil and also due to the fact that it is held down by means of the cap engaging the shoulder 5.

What I claim is:

1. In combination, an electrode, a dowel forced into the end of said electrode, and a cap forced over the end of said electrode and holding the dowel from rotary and vertical displacements.

2. In combination, a carbon electrode, a dowel having a corrugated shank forced into the end of said electrode, and a crown cap forced over the end of the electrode and holding said dowel from rotary and vertical displacements.

3. In combination, a carbon electrode the end of which is tapered and perforated to a

slight depth, a dowel having a corrugated shank projecting within said perforation, a shoulder on said dowel to limit its downward movement, a squared enlargement on said dowel above said shoulder, a cap having a fluted petticoat engaging the tapered end of said electrode, and a squared perforation en-

gaging said enlargement, and a bead around the perforation in said cap forming a homogeneous mass with said enlargement. 10

In witness whereof, I hereunto subscribe my name this 23rd day of July 1923.

EDWIN J. REICH.
